(57) **CLAIM**

The ornamental design for a surface configuration of a console for a vehicle, as shown and described.

DESCRIPTION

FIG. 1 is a right perspective view of a surface configuration of a console for a vehicle according to our novel design; and, FIG. 2 is an enlarged left perspective view of surface configuration of a console for a vehicle according to our novel design.

The dash lines included depict environment and are not part of the claimed design.

1 Claim, 2 Drawing Sheets

FIG. 1

FIG. 2
